UNITED STATES PATENT OFFICE.

EDWARD E. BARTELS, OF WHITING, INDIANA, ASSIGNOR TO STANDARD OIL COMPANY, OF WHITING, INDIANA, A CORPORATION OF INDIANA.

PRODUCING RESIDUAL OIL PRODUCTS.

No Drawing.

Application filed November 17, 1924. Serial No. 750,489.

The present invention relates to improvements in the handling of pressure tar, by which term is designated the residual product of the conversion under pressure of hydrocarbon oils into gasoline, the lighter portions thereof (containing gasoline) having been removed. An average pressure tar, resulting from the operation of the Burton process, for example, may have a Baume 10 gravity of 18°.

In the running down of pressure tar for the formation of various grades of road oils and fluxing oils, it has hitherto been customary to employ series of stills in ordinary continuous operation, the operation of the entire battery or series of stills being controlled for the production, as a residue, of a specific one of the commercial grades of such oils. Thus it has been customary to 20 produce from pressure tar in this manner four or more products of increasing viscosity, some being designated as road oils and the heaviest as fluxing oils. The lightest of these products, the first road oil, may have, 25 for example, a viscosity of 1.5 Engler. The heaviest or fluxing oil product may have a viscosity of 6 Engler, intermediate road oil products having viscosities, for example, of 2.5 Engler and 3 Engler, the viscosity being 30 measured in each case at 212° F.

Variation in the simultaneous market requirements for the various products has made this method of running very uneconomical and disadvantageous, usually it has 35 been found necessary to make certain of the products in batch stills while the battery is in use for the manufacture of the products for which there is the greatest demand.

In carrying out the present invention, a 40 battery or series of successive stills is used in running down the pressure tar; an intermediate residual product is drawn off from an intermediate still in the system, this corresponding to the lightest of the desired 45 commercial products, and a residue or tar is simultaneously drawn off from the end of the system, this corresponding to the heaviest of the commercial products. For example, if a system consisting of ten stills 50 is operated continuously on pressure tar of

the character above set forth, the light road oil (viscosity 1.5 Engler) may be drawn off as a residue, for example, from the seventh still, and the fluxing oil (viscosity 6 Engler) may suitably be drawn off as a residue from 55 the last still. The intermediate products of the desired viscosities may then be produced in the desired quantities in accordance with market demands by mixing or blending the heavy residue and the intermediate product 60 drawn off. Thus, by mixing them in the proportion of about 45 to 55, the second grade of road oil above referred to (viscosity 2.5 Engler) may be produced and by mixing them in the proportion of about 70 65 to 30, the heaviest road oil (viscosity 3 Engler) may be produced.

It is to be understood that the figures and proportions above given are intended for purposes of illustration only, and that the 70 process may readily be adapted for use in connection with any type of residual products produced by continuous distillation, either with fire alone or with fire and steam.

I claim:

1. The method of forming a plurality of residual products by continuous distillation of a hydrocarbon oil in a succession of stills, which comprises drawing off as a residual 75 from an intermediate one of said stills the desired product of the lightest grade, drawing off from the end still a residue having the properties of the desired product of the heaviest grade, and blending said products to produce the desired products of intermediate grade.

2. The method of reducing pressure tar for the formation of a plurality of residual products of predetermined viscosities comprising subjecting the pressure tar to continuous distillation with fire and steam in a succession of stills, drawing off as a residue from an intermediate one of said stills an oil of the viscosity desired in the lightest product, removing from the final still a 90 residue having a viscosity of about 6 Engler at 212° F., and blending said residues to produce intermediate products of desired viscosities.

EDWARD E. BARTELS.
